UNITED STATES PATENT OFFICE

HERBERT V. HENDERSON, OF DETROIT, MICHIGAN, ASSIGNOR TO CHRYSLER CORPORATION, OF DETROIT, MICHIGAN, A CORPORATION OF DELAWARE

DESIGN FOR AN INSTRUMENT BOARD

Application filed June 15, 1929. Serial No. 31,709. Term of patent 3½ years.

To all whom it may concern:

Be it known that I, HERBERT V. HENDERSON, a citizen of the United States, residing in the city of Detroit, county of Wayne, and State of Michigan, have invented a new, original, and ornamental Design for an Instrument Board, of which the following is a specification, reference being had to the accompanying drawings, forming a part thereof, in which—

Fig. 1 is a front elevation of an instrument board.

Fig. 2 is a plan view of Fig. 1.

Fig. 3 is a sectional view on line 3—3 of Fig. 1.

I claim:

The ornamental design for an instrument board substantially as shown.

HERBERT V. HENDERSON.
